UNITED STATES PATENT OFFICE.

ALBERT M. BURRITT, OF WATERBURY, CONNECTICUT, ASSIGNOR TO THE
A. BURRITT HARDWARE COMPANY, OF SAME PLACE.

FIRE-EXTINGUISHER.

SPECIFICATION forming part of Letters Patent No. 257,654, dated May 9, 1882.

Application filed February 1, 1882. (No model.)

To all whom it may concern:

Be it known that I, ALBERT M. BURRITT, of Waterbury, in the county of New Haven and State of Connecticut, have invented new 5 Improvements in Fire-Extinguishers; and I do hereby declare the following, when taken in connection with accompanying drawings and the letters of reference marked thereon, to be a full, clear, and exact description of the 10 same, and which said drawings constitute part of this specification, and represent, in—

Figures 1 and 2 vertical central sections, showing different plugs; Fig. 3, a modification.

This invention relates to an improvement in 15 distributors for that class of fire-extinguishers in which a line of pipe is led to the apartment to be protected and there fitted with a distributor, which, when the water is let on, will distribute the water in the form of spray to extinguish the fire that may have accidentally 20 occurred in the apartment, the object of the invention being the construction of a distributor which will throw the water over a larger space than the common perforated rose, and 25 which may also be pendent from the ceiling, and thereby distribute the water over a very large apartment; and the invention consists in a disk attached to the discharge-nozzle a little distance from the discharge, the plane of the 30 disk being at right angles to the line of discharge, and the disk constructed with a flange projecting toward the discharge and perforated, whereby the water flowing with force 35 through the nozzle will first strike the disk, then spread radially in all directions, will be discharged through the perforations in the rim, and turned upward over the rim, will also throw an unbroken thin sheet of water of umbrella-like form, of which the distributor forms 40 the center; and, also, in the arrangement of the plug whereby this distribution of water is facilitated, as more fully hereinafter described.

A represents the nozzle, to which the water is led through the conducting-pipes in the 45 usual manner, and arranged at the point where the distribution is to be made. B is a cup-shaped disk, preferably flat bottom, arranged in a plane at substantially right angles to the water-way or discharge and a little distance 50 from the discharge-opening. It is attached to

the nozzle by arms *a*, or otherwise. The rim *b* of the disk turns toward the nozzle and stands preferably at an angle of about thirty degrees to the plane of the disk—that is, expanding toward the nozzle. The rim is smooth 55 upon its inner surface, but with numerous perforations, *d*, made therein. Then, when the water is let on, it passes from the nozzle and strikes with force upon the bottom of the disk, and there spreads in all directions, striking 60 the rim. A portion passes out through the perforations in the form of spray, as it does in the usual perforated rose. The balance is turned upward by the inner surface of the rim, and forced over the edge of that rim in a thin umbrella-like sheet, of which the distributor forms 65 the center, as indicated in broken lines, Fig. 1. This sheet will be thin, and will be thrown at a great distance, breaking eventually into the form of spray, and thus this sheet, combined 70 with the spray directed through the perforations, will distribute to all parts of the apartment. Other perforations may be made in the bottom of the distributor.

Instead of making the distributor flat-bottomed, as seen in Fig. 1, it may be concave shape, as seen in Fig. 3—that is, shaped similar to the outer end of the usual rose. In this case the water will be discharged through the perforations in the usual manner, and also over the 80 edge in a sheet, as before described.

In Fig. 1 C is the plug, of conical shape, soldered or connected to the nozzle by a fusible connection, with a spindle, D, extending therefrom down through the bottom of the cup. 85 When this plug is liberated by heat, which may accidentally occur in the apartment, it is forced down upon the bottom of the distributor directly in line of the discharge, so that the water will strike upon this conical shape 90 and be spread in all directions more easily and readily than if it strike upon the flat bottom.

Instead of soldering the plug in the end of the nozzle, it may be secured by solder over the end of the spindle, as indicated at *e*, which 95 attaches the spindle to the distributor. In this case the distributor and its connection must be of sufficient strength to support the plug against the pressure of water. Another advantage of this last construction is that the 100

plug is held in place by the distributor, which is screwed to the end of the nozzle. Hence the nozzle may be unscrewed and the plug removed or examined at any time without disturbing the fusible connection or support.

In Fig. 2 I show the plug C as presenting a convex or parti-spherical shape, so that as it falls into the distributor it will be thrown about therein to clear the opening from any obstructions, as described in a previous patent to me.

I do not wish to be understood as claiming broadly a disk arranged in front of the discharge upon which the water will strike and be thereby spread, as such, I am aware, is not new.

15 I claim—

1. The distributor consisting of the cap-shaped disk attached to the nozzle and arranged in a plane at substantially right angles to the discharge and a short distance therefrom, the rim of the said cup perforated, substantially as described.

2. The distributor consisting of the cap-

shaped disk attached to the nozzle and arranged in a plane at substantially right angles to the discharge and a short distance therefrom, the rim of the said cap perforated, with a conical plug to close the nozzle, secured by a fusible connection, the spindle of the plug extending through the bottom of the distributor, substantially as and for the purpose described.

3. The distributor consisting of the cup-shaped disk attached to the nozzle and arranged in a plane at substantially right angles to the discharge and a short distance therefrom, the rim of the said cap perforated, with a plug to close the nozzle, its spindle extending through the distributor and secured by a fusible connection between the spindle and the distributor, substantially as described.

ALBERT M. BURRITT.
